UNITED STATES PATENT OFFICE.

ERIK WM. NELSON, OF NEW ROCHELLE, NEW YORK.

PROJECTOR.

1,336,479.

Specification of Letters Patent. Patented Apr. 13, 1920.

Application filed January 13, 1919. Serial No. 270,821.

To all whom it may concern:

Be it known that I, ERIK W. NELSON, a citizen of the United States, residing in the city of New Rochelle, in the State of New York, have invented certain new and useful Improvements in Projectors, of which the following is a specification, reference being had to the accompanying drawing, forming a part hereof.

10 This invention relates to projectors for moving pictures and has for its object to produce a projector which can be sold at a very low price, shall be exceedingly simple in construction and not liable to derangement even in the hands of the inexpert, and shall be small in compass and light in weight. In accordance with the invention the operating shaft has its bearing in the casing which supports the sprocket drums, 15 the film feeder, the lens and the shutter, and carries a gear with crown teeth and internal teeth, with which the sprocket drums, feeder and shutter shaft are directly engaged, without intermediate gearing of any kind, such 20 gear also forming part of the casing which completely incloses the several intermeshing gears and also carrying the pulley over which passes the band for driving the lower take-up spool. The invention will be more 25 fully explained hereinafter with reference to the accompanying drawing in which it is illustrated, and in which—

Figure 1 is a view in side elevation of a complete projector which embodies the invention, the source of light not being shown and the condenser being partly broken away.

Fig. 2 is a view in side elevation, on a larger scale than that of Fig. 1, of the projector mechanism.

Fig. 3 is a view in section on the irregular plane indicated by the broken line 3—3 of Fig. 2, looking in the direction of the arrows.

The entire mechanism may be mounted 45 on a bed plate *a*. To the bed plate is secured a casing *b*, which can be made conveniently as a die casting, having a vertical wall *b'* and a flange *b''*, the upper part being formed on the arc of a circle. Centrally 50 with respect to the upper part of the casing is formed a sleeve bearing *b''*, which may be extended in both directions from the vertical wall *b'*. In the bearing *b''* is mounted the crank shaft *c* which is formed with or has 55 secured thereto at one end a crank *c'*, while at the other end it has secured thereto a gear

d which is formed with internal gear teeth *d'* and crown gear teeth *d''*. The gear *d* is also formed with a pulley *d'* over which passes the usual spiral wire driving band *e* for driving in the usual manner the take-up spool *f* which may be supported by a bracket *f'*. The delivery spool *g* may be supported in like manner by a bracket *g'* secured to the top of the casing *b*.

The casing *b* is also formed with bearing sleeves *b'*, above and below the bearing *b''* of the crank shaft *c*, to receive respectively the shafts *h* on which are mounted the sprocket drums *h'* by which the film is fed conveniently so as to form loops between the sprocket drums and the intermitting feeder. With each sprocket drum co-acts a presser roll *i* carried by a lever *i'*, pivoted at *i''* on the casing and engaged by a spring-pressed plunger *i''* to hold the presser roll in operative or inoperative position as may be desired. Each shaft *h* is provided with a gear *h''* which meshes directly with the internal gear teeth *d'*, so that the sprocket drums are 70 driven directly by the gear *d* without intermediate gearing.

The casing *d* has also formed therewith a bearing sleeve *b''* which receives a shaft *k*. The latter has secured thereto a cam *k'* 85 which engages and actuates the intermitting film feeder *k''* as shown in Letters Patent of the United States No. 1,268,874. The film traverses a guide *l* against which it is pressed by a friction pad *l'*, held in place by a gate *l''*. The shaft *k* has at its inner end a pinion *k''* which meshes directly with the internal teeth *d'* of the gear *d*.

The flange *b''* of the casing *b* has also formed therewith a bearing sleeve *b''* which receives the shaft *m* on which is secured the shutter *m'*. At its inner end the shaft *m* is provided with a pinion *m''* which meshes directly with the crown teeth *d''* of the gear *d*, this arrangement permitting the shutter 95 to be driven directly from the gear *d* without intermediate gearing.

Also mounted on the casing *b* is a cylindrical shell *n* to receive the lens tube *o*, the shell *n* having an oblique slot *n'* to receive a 105 screw pin *o'* set into the lens tube *o* for the purpose of effecting conveniently the focusing of the lens.

It will be observed that the gear *d* itself forms part of the inclosing casing and protects the intermeshing gears from dust and from entanglement with the film. It will 110

also be observed that the number of working parts is reduced to a minimum and that the whole structure is exceedingly compact and is of low cost to manufacture.

5 I claim as my invention:

1. A projector for moving pictures comprising a flanged casing provided with bearings for the several working parts, a driving shaft mounted in the casing, a driving gear fixed on the driving shaft and conforming to the flange of the casing to complete the inclosure and formed with internal gear teeth, and sprocket drums and a film feeding device all mounted on the casing 10 and having pinions engaging the internal teeth of the driving gear.

2. A projector for moving pictures comprising a flanged casing provided with bearings for the several working parts, a driving 20 shaft mounted in the casing, a driving gear fixed on the driving shaft and conforming to the flange of the casing to complete the inclosure and formed with crown teeth and a shutter having its shaft mounted in a bear-

ing formed therefor on the flange of the casing and having a pinion engaging the crown teeth of the driving gear.

3. A projector for moving pictures comprising a flanged casing formed with bearing sleeves for the several working parts, a 30 driving shaft mounted in one of said bearings, a driving gear having internal teeth and crown teeth and fixed on the driving shaft and completing the inclosure of the casing, a shutter shaft and shutter mounted 35 in one of the bearings on the casing and having a pinion in mesh with the crown teeth of the driving gear, sprocket drums and shafts mounted in other bearings on the casing and having pinions meshing with 40 the internal teeth of the driving gear and a film feeding device and shaft mounted in another of the bearings on the casing and having a pinion in mesh with the internal teeth of the driving gear.

45 This specification signed this 11th day of January, A. D. 1919.

ERIK WM. NELSON.
